US00D783007S

(12) **United States Design Patent** (10) **Patent No.:** **US D783,007 S**
(45) **Date of Patent:** **** Apr. 4, 2017**

(54) **HIGH CAPACITY SECTOR MOUNT**

(71) Applicant: **CommScope Technologies LLC**,
Hickory, NC (US)

(72) Inventors: **Alan J. Skrepinski**, Plano, TX (US);
Kevin L. Rovell, Fort Worth, TX (US);
Kevin R. Paswalk, Watuaga, TX (US)

(73) Assignee: **CommScope Technologies LLC**,
Hickory, NC (US)

(**) Term: **14 Years**

(21) Appl. No.: **29/525,322**

(22) Filed: **Apr. 28, 2015**

(51) **LOC (10) Cl.** **14-03**

(52) **U.S. Cl.**

(57) **CLAIM**

The ornamental design for a high capacity sector mount, as shown and described.

DESCRIPTION

FIG. 1 is a front perspective view of the high capacity sector mount showing our new design;

FIG. 2 is a rear perspective view thereof;

FIG. 3 is a front view thereof;

FIG. 4 is a left side view thereof;

FIG. 5 is a right side view thereof;

FIG. 6 is a rear view thereof;

(Continued)

FIG. 7 is a top plan view thereof; and,
 FIG. 8 is a bottom plan view thereof.
 The dashed lines are included for the purpose of illustrating
 environmental structure that forms no part of the claimed
 design.

1 Claim, 8 Drawing Sheets
